UNITED STATES PATENT OFFICE.

ADOLF POLLATSEK, OF BROOKLYN, NEW YORK.

LABELING-MACHINE.

1,295,592.

Specification of Letters Patent. Patented Feb. 25, 1919.

Application filed August 31, 1918. Serial No. 252,234.

To all whom it may concern:

Be it known that I, ADOLF POLLATSEK, a citizen of the United States, and a resident of the city of New York, borough of Brooklyn, in the county of Kings and State of New York, have invented a new and Improved Labeling-Machine, of which the following is a full, clear, and exact description.

This invention relates to a labeling machine and has for an object the provision of an improved construction which is semi-automatic and which will apply and press labels on bottles, cans and the like of different sizes and shapes.

Another object of the invention is to provide an arrangement of label applying mechanism which will apply labels automatically to bottles manually fed into the machine and manually removed.

A still further object of the invention is the provision of a machine in which the parts may be adjusted for taking care of different sized bottles and labels applied thereto with equal pressure regardless of the size of the bottles.

In the accompanying drawings:

Figure 1 is a side view of a labeling machine disclosing an embodiment of the invention.

Fig. 2 is a longitudinal vertical section through Fig. 1.

Fig. 3 is a transverse sectional view through Fig. 1 on line 3—3, the same being on an enlarged scale.

Referring to the accompanying drawings by numerals 1 indicates a frame provided with brushes and connecting bars for supporting various parts of the machine. Arranged adjacent frame 1 is an auxiliary frame 2 provided with a number of uprights 3 having ways or grooves therein for receiving the sliding members 4 of the adjustable frame 5, said adjustable frame 5 having a flexible support 6 for bottle 7. The frame

5 is provided with racks 8 and 9 meshing with pinions 10 and 11, said pinions being rigidly secured to shaft 12 which is provided with a hand wheel 13, whereby whenever hand wheel 13 is rotated the racks and also frame 5 will be moved upwardly or downwardly according to the rotation of the hand wheel.

After the frame has been properly adjusted for the particular sized bottle 7 it is allowed to remain stationary, while the respective bottles 7 are placed on the support

6 and removed successively as the labels are applied thereto.

In order to provide labels with adhesive and also to provide labels sufficiently moist to properly lay on the bottle when pressed against the same an endless belt 14 is provided which passes over rollers 15, 16, 17 and 18. Each of these rollers is provided with a sprocket wheel adjacent each end, the teeth of which pass through the eyelets 19 and 20 (Fig. 3), whereby the power from the roller 15 will be transmitted to the other rollers and there will be no slipping of the belt. The power roller 15 is connected with the power wheel 21, which power wheel receives power from any suitable source not shown. The roller 17 is partially submerged in a paste container 22 so as to receive paste therefrom and supply it to the outer face or surface of the belt or apron 14 from which the paste is transmitted to the labels 23 as the same are brought into contact therewith. The labels 23 are arranged in a stack on a pivotally mounted support 24 and positioned so that their rear or back face will be next to the belt or apron 14. At the proper time the shaft 25 to which the support 24 is rigidly secured is tilted sufficiently for causing one end of the stack of labels 23 to engage the belt whereupon the belt 14 will remove the upper label and pass the same beneath the moistening roller 26. Roller 26 is an idler and carries a covering fabric of any suitable kind which is maintained moist by water from the container 27, which water drips slowly through the discharge nozzle 28. In this way each label receives paste from the belt or apron 14 and water from the idler 26 so as to prevent any curling when applied to the bottle. Some paste may be applied to the idler 26 from time to time, but this is kept in a more or less liquid state and consequently will not injuriously affect the label as it passes therebeneath.

During the operation of the machine the label travels from the idler 26 over the power roller 15 and is removed by the shelves 29 and 30, said shelves preferably having a sharp edge 31 adjacent the belt or apron 14 so as to in a certain sense peel off the label from the apron. As the adhesive is comparatively liquid at this stage removal of the label can be easily accomplished as the apron continually urges the label forward so that it slides on to the shelves 29 and 30, which shelves are spaced apart as shown in

Fig. 3 for allowing the pressure foot 32 to pass downwardly and move the label against the bottle 7. The pressure foot 32 will press merely the central part of the label against the bottle and the remaining part of the label will be pressed against the bottle by rollers 33 and 34 hereinafter fully described. The pressure foot 32 is connected with a rack 35 which meshes with pinion 36, said pinion 10 being rigidly secured to shaft 37, which shaft carries a sprocket wheel 38 over which the chain 39 passes. Chain 39 also passes over sprocket wheel 40 which sprocket wheel is rigidly secured to shaft 41. In order to 15 provide a proper back and forth rotary movement of the sprocket 40 and the consequent back and forth movement of the parts associated therewith shaft 41 is rigidly secured to lever 42. Auxiliary levers 43 and 20 44 are also rigidly secured to shaft 41 and may be secured to each other. Lever 44 is pivotally connected at 45 to link 46 which link is reciprocated by the wheel 47 to which it is pivotally connected by the wrist pin 48. 25 Wheel 47 is rigidly secured to the shaft 49 to which the power roller 15 is secured and also to which the power wheel 21 is secured. When the machine is not resting the wheel 47 is continually rotating and consequently 30 continually moving link 46 back and forth and oscillating lever 44, shaft 41 and associate parts so as to cause the pressure foot 32 to move up and down, namely from the position shown in Fig. 2 downwardly until 35 it is pressing the label against the bottle 7 and then back to the position shown in Fig. 2. The size of the sprocket wheels 38 and 40 and the size of the pinion 36 are of proper proportion to provide this movement by the 40 back and forth movement of lever 44 and associate parts. Lever 43 is pivotally connected to link 50 which link is pivotally connected at 51 to arm 52 which arm is rigidly secured to the shaft 25 carrying the support 45 24 holding the labels 23. By this connection the support is moved toward and from the belt or apron 14 in proper timed relationship to the movement of the pressure foot 32 and associate parts whereby the 50 labels will be properly spaced so that a label will be on the shelves 29 and 30 when the pressure foot moves downwardly therebetween. Lever 42 is pivotally connected to a link 53 which is formed with a slot 54 at 55 the lower end, which slot accommodates the clamping screw 55, which clamping screw passes through a slot 56 in the lever 57. Lever 57 is rigidly secured to the shaft 58, said shaft carrying an arm 59 also rigidly 60 secured thereto and carrying a connecting link 60, which is pivotally connected at 61 to arm 59 and pivotally connected at 62 to a lever 63. Lever 63 is pivotally mounted at 64 on the frame 5 and carries an operating 65 link 65 which is pivotally connected with

lever 63 at 66 and to the lower end of links 67 and 68 at 69; thereby whenever link 65 is raised these links will also be raised and the auxiliary links 67' and 68' will be moved laterally or horizontally. The auxiliary 70 links 67' and 68' are pivotally connected to the levers 70 and 71 respectively, said levers being pivotally mounted at 72 and 73 on frame 5. These levers carry arms 74 and 75 which are pivotally connected thereto and 75 which are bent to the shape shown in Fig. 3. These levers are provided with roller retaining brackets 76 and 77, each of said brackets carrying a spring 78 bearing at the center against the bracket and at the ends 80 against the ends of the journal member 79 of the respective rollers 33 and 34. As shown in Fig. 2 the depending ends of the respective brackets 76 and 77 are slotted so that the square ends of the shaft 79 may 85 slide back and forth therein without rotating, spring 78 normally holding the rollers in an outer position. This shaped end of the bracket 76 is desirable in order to prevent the ends of the brackets 76 and 77 from 90 striking the bottle while at the same time allowing a horizontal independent motion of the respective rollers so as to take care of any slight inequalities in the bottle or label as the case may be. 95

In order to cause the rollers to properly engage the label and press the same against the bottle as shown in Fig. 3, links or piston rods 80 and 81 are pivotally connected to the respective arms 74 and 75, said piston rods carrying stops 82 and 83 at their lower ends, said stops being engaged by the respective springs 84 and 85 surrounding the piston rods. The upper end or the end opposite the stops 82 and 83 of the respective 100 springs engages the caps 86 and 87 of the cylinders 88 and 89. These cylinders are pivotally mounted at 90 and 91 on the auxiliary links 67' and 68'. These springs ordinarily are sufficiently stiff to prevent any 105 movement of the rods 80 and 81, but in the case of a peculiar shaped bottle said springs will operate for allowing the rollers to pass properly thereover. In addition these springs will allow a yielding action in case 110 a larger bottle is supplied than the movable frame 5 is adjusted to accommodate. 115

When the parts are in the position shown in Figs. 1 and 2 a label has just been applied, the bottle 7 is removed and a new bottle substituted while the machine continues to rotate. As soon as the label 23' reaches the dotted position indicated on the shelves 29 and 30 the pressure foot 32 will move downwardly and press the same downwardly 125 between the two shelves and against the new bottle 7. As the pressure foot moves downwardly the rollers 33 and 34 will also move downwardly as indicated in dotted lines in Fig. 3, this downward movement of the 130

rollers being an idle movement. As the pressure foot 32 and associate parts move upwardly rollers 33 and 34 will also move upwardly to the position shown in Fig. 3 and 5 will then move downwardly and on the second movement will engage the label and press the same against the bottle. The second downward movement of the pressure foot 32 is idle, and will do no injury as there 10 is no label on the shelves 29 and 30. After the label has been applied and the rollers 33 and 34 move out of contact therewith the bottle is removed and a new bottle substituted. This action is continued as long as 15 the machine is in operation.

What I claim is:

1. A label applying machine of the character described comprising a support for a bottle, means for carrying a number of 20 labels, a paste belt for supplying paste to said labels successively and moving the same to a predetermined point, means for causing the labels to successively at spaced intervals engage said belt, a pair of brackets for receiving the labels from said apron, a pusher foot for moving the labels from said bracket to said bottle, and spreading means for spreading and pressing the label against the 25 bottle.
2. A label applying machine for bottles comprising means for supporting a quantity of labels, means for applying paste to said labels successively and moving the labels to a discharge point, a pusher foot for moving 30 the labels from a discharge point to a point in contact with the bottle, and a pair of spreading rollers for spreading the label on said bottle and pressing the same against the bottle.
3. A label applying machine for bottles 35

comprising means for supporting a bottle in a given position, means for depositing a label on said bottle, said means consisting of a traveling feeding belt, stripping members for removing the labels successively from 45 the belt, and a pusher foot for pressing the labels from the stripping means to a position in contact with the bottles on said support, and spreading means for spreading the label and pressing the same against the 50 bottle.

4. A labeling machine comprising means for supporting a bottle, a pair of brackets arranged above the bottle, a traveling belt for depositing a label on said brackets, a 55 pressure foot arranged adjacent said brackets, means for reciprocating said pressure foot, the movement of said pressure foot in one direction causing said label to be moved against said bottle, and means for engaging 60 and spreading the label over the bottle after the pressure foot has been disengaged therefrom.

5. A label applying machine for bottles comprising an adjustable support for bottles, means for depositing a label on the bottles as they are successively placed on said support, a pair of spreading rollers for spreading said labels on said bottles, a pair 65 of arms carrying said rollers, means carried by the arms for resiliently holding said rollers in a given position, a plurality of levers for actuating said arms, a resilient connection between said arms and certain of said 70 levers for permitting said arms to cause the rollers to accommodate themselves to different shaped bottles, and means for actuating said levers.

ADOLF POLLATSEK.
